Attorneys

UNITED STATES PATENT OFFICE.

EARL W. WINANS, OF DETROIT, MICHIGAN.

ANTIFREEZING PLUG.

Application filed October 3, 1919. Serial No. 328,324.

To all whom it may concern:

Be it known that I, EARL W. WINANS, a citizen of the United States of America, residing at Detroit, in the county of Wayne 5 and State of Michigan, have invented certain new and useful Improvements in Anti-freezing Plugs, of which the following is a specification, reference being had therein to the accompanying drawings.

10 This invention relates to safety plugs for liquid containers and the object of the invention is to provide a safety device applicable to all liquid containers to prevent bursting thereof, through freezing of their 15 contents, said device having a special value as applied to water pipes and to the water jackets of explosive engine cylinders.

In the drawings:

Figure 1 is a sectional elevation showing 20 the application of the invention to an ordinary jug or a bottle;

Figure 2 is a cross section of the water jacket of an engine to which the invention is applied;

25 Figure 3 is a sectional view showing the application of the invention to a water pipe.

Figures 4 and 5 are views of two diaphragms weakened to insure bursting when subjected to predetermined pressures.

30 In these views the reference character 1 designates a jug or bottle having a cork or stopper 2 engaging its mouth. The upper end portion of a tube 3 is extended centrally through the stopper 2, and fixedly secured to said stopper in any suitable manner. Said tube extends downwardly into the central portion of the receptacle 1 and its lower end is there closed by a cap 4 formed of a material having a considerable less strength 35 than the wall of the receptacle. Thus, when the contents of the receptacle begin to freeze, the resultant pressure within the receptacle will fracture the cap 4 rather than the receptacle itself and the pressure will then be relieved.

40 Referring now to Figure 2, 5 designates the water jacket of an explosive engine, and 6 is a tubular plug having screw-threaded engagement with a wall of said water jacket 50 adjacent the bottom thereof, said plug terminating at its inner end in the central portion of the lower part of the water jacket. A clamping ring 7 is screwed upon the inner end of said plug and serves to clamp the disc shaped closure 8 against said end, a packing ring 9 being preferably engaged between the

marginal portion of said closure and said ring. The disc 8 is formed of a material having ample strength to resist such pressures as may ordinarily arise within the 60 water jacket chamber, said disc nevertheless, being considerably weaker than the wall of the water jacket. Thus said disc may be formed of lead or some other soft metal proportioned in thickness to insure yielding upon creation within the water jacket chamber of a pressure considerably less than that required to fracture the wall thereof. Thus, when the contents of the water jacket commence to freeze the pressure will not be permitted to build up to a dangerous point before fracture of the closure 8 occurs, permitting the major portion of the water within 65 said jacket to escape through the plug 6.

In Figure 3, 10 designates an ordinary water pipe, and 11 a fitting interposed in said pipe, providing a chamber having an area considerably greater than that of the pipe. The wall of said fitting is adapted for screw-threaded engagement by a plug 12, 70 extending into the central portion of the fitting and provided at its inner end with the closure 13 having a predetermined strength considerably less than that of the fitting itself, the construction and mounting 75 of said closure corresponding to that of the plug 6 and closure 8 already described. The plug 12, however may be provided with an internally threaded outer portion 13^a for engagement by a waste pipe 14, which will conduct the escaping water to any desired point, when bursting of the closure 13 occurs 80 through an initial freezing of the water in 85 said pipe.

In each of the applications of the invention, as above described, it will be noted that the plug is extended some distance into the receptacle, this being done for the reason that freezing occurs first adjacent the receptacle walls and therefore will build up 90 a pressure within the receptacle sufficient to break the closure carried by the inner end of the plug before the temperature of the liquid in contact with said closure has been reduced to the freezing point. This feature of the invention is highly important, since if the liquid adjacent the safety closure freezes prior to yielding of said closure, the ice thus formed will act as a reinforcement to said closure, so that the latter can not be depended upon to yield under the predetermined conditions, and may resist the increas- 95 100 105 110

2
ing pressure resulting from progressive freezing until said pressure becomes high enough to burst the receptacle.

Instead of having the closure of the relief tube of a uniform thickness sufficiently reduced to yield under abnormal pressure, there may be employed such discs or dia-
phragms as shown in Figures 4 and 5, the former being weakened by an annular chan-
nel 15 and the latter by partially shearing out its central portion so as to produce a relatively thin neck portion 16.

What I claim as my invention is:

In a device of the class described, the com-

bination with a liquid container having an opening therein, of a hollow plug engaging the opening in said container, a tube projecting inwardly from said plug and terminating about the center of said container, a disk-shaped closure engaging the inner end of said tube and having a predetermined strength less than that of said tube and the wall of said container, and a clamping ring engaging the edges of said closure and holding the latter in place, said closure being weakened adjacent to the edges thereof.

In testimony whereof I affix my signature.

EARL W. WINANS.
